PRIMING DEVICE FOR PUMPS

Harold A. Bentley, Battle Creek, Mich., assignor, by
mesne assignments, to American Fire Apparatus Com-
pany, Battle Creek, Mich., a corporation of Michigan

Application October 14, 1955, Serial No. 540,465

5 Claims. (Cl. 137—202)

This invention relates to priming devices for pumps well adapted for priming the pumps of mobile fire fighting apparatus in which the pump is powered by the engine.

The main objects of this invention are:

First, to provide a primer for engine driven and engine primed pumps which is highly efficient and minimizes the likelihood of damage to the engine.

Second, to provide a priming device of this character which is of large capacity and quickly evacuates the air from the engine driven pump, the engine also constituting the source of vacuum.

Third, to provide a priming device having these advantages which is not likely to become waterlogged.

Objects relating to details and economies of the invention will appear from the description to follow. The invention is defined and pointed out in the claims.

A preferred embodiment of the invention is illustrated in the accompanying drawing, in which:

Fig. 1 is a fragmentary elevational view illustrating the primer of my invention in operative relation to a pump and an engine which are conventionally shown.

Fig. 2 is an enlarged vertical section on a line corresponding to line 2—2 of Fig. 1 with certain parts shown in full lines.

Fig. 3 is an enlarged fragmentary view partially in section on a line corresponding to line 3—3 of Fig. 1.

In the accompanying drawing 1 represents a centrifugal pump, 2 an engine, and 3 the manifold thereof. The driving connection for the engine to the pump is not illustrated. It will be appreciated that inasmuch as the source of suction for evacuating the air from the pump is the engine powering the pump it is extremely important that the primer act efficiently, otherwise the engine might be injured or rendered inoperative at a critical time. It is also important that while the primer is automatic in operation that the manual starting and stopping thereof be simple and positive.

The primer proper comprises a primer body or casing 4 defining a main float chamber 5 having an inlet 6 connected to the pump casing, desirably by a flexible conduit 7. The float chamber has a drain 8, the inlet and drain being provided with a two-way valve designated by the numeral 9. This valve may desirably be that shown in Fig. 3 with the drain 8 substituted for the air vent. It will be understood that the valve is such that the drain is closed when the suction inlet connection to the pump is open and that the drain is open when the suction inlet is closed.

The casing 4 has an opening 10 in the top thereof closed by the base 11 of the valve chamber and auxiliary float casing 12 defining an auxiliary float chamber 13. The casing 12 has a removable top 14 provided with a suction inlet 15. This inlet is provided with a two way control valve 16 which is connected by the conduit 17, desirably flexible, to the manifold 3 of the engine 2. A return check valve 18 is positioned between the valve 16 and the manifold. The valve 16 has an air vent 116.

2

The auxiliary float chamber 13 is connected by the port 19 to the main float chamber 5. It is also connected to the main float chamber by the water drain 20. The main float 21 is provided with an arm 22 pivoted at 23. The stem 24 of the valve 25 which coacts with the port 19 rests upon the float arm 22 so that the valve 25 is closed by the water rising in the main float chamber. It will be understood that when the air is exhausted from the pump and the pump is primed, water will flow into the float chamber 5 actuating the float to close the valve 25.

The safety valve 26 coacts with the port 27 of the suction line and is carried by the auxiliary float 28 disposed in the auxiliary float chamber and provided with a guide stem 29 reciprocating in the opposed guides 30 and 31. The purpose of these guides is to minimize the likelihood of the float 28 jamming or becoming inoperative.

A check valve 32 is provided for the drain 20 of the auxiliary float chamber 13. This check valve 32 is in normal operation of the apparatus seated by suction in the suction chamber 13. It is, however, lighter than water so that in the event of flooding of the main float chamber 5 it is seated by the water therein. The vent 20 has an enlarged lower portion 33 which constitutes a cage for the check valve 32. In the embodiment illustrated the guide plate 34 for the stem 24 of the valve 25 is extended partially across the bottom of the enlargement 33 to retain the check valve 32 as is illustrated in Fig. 2.

The valve 35 for the vent port 36 of the auxiliary float chamber is mounted on the stem 24 of the valve 25 so that the vent port 36 is opened when the valve 25 is seated and is closed when the valve 25 is opened. The top 14 of the auxiliary housing 12 is provided with a shield 37 for the valve 35.

The valves 9 and 16 are in the embodiment illustrated connected by the rock shaft 38 sleeved upon the valve stems 39 and 40 of the valves 9 and 16 and provided with an arm 41 to which the operating rod 42 is connected. The spring 43 is connected to the housing or casing 12 and to the arm 41 to automatically return the valves 9 and 16 to closed position, it being contemplated that the operator will hold the valves open against the tension of this spring until the pump is primed and that the valves will automatically close when the rod 42 is released. In normal operation little if any water will enter the auxiliary float chamber but should that occur, for example as the result of the operator holding the valve 16 open after the pump has become primed, the valve 26 closes and prevents water entering the manifold. The check valve 32 insures the rapid draining of the float chamber when the valve 16 is adjusted to venting position and the valve 9 to drain position.

I have not illustrated means for supporting this control rod, but it will be understood that it is desirably supported on some convenient part of the apparatus. The primer is mounted on some convenient part of the apparatus as indicated conventionally at 44.

Reference is made to the Adney and Barton Patent No. 2,322,910, issued June 29, 1943 inasmuch as my present invention is an improvement upon and embodies certain features of that patent.

I have illustrated my invention in a highly practical embodiment thereof. I have not attempted to embody other adaptations or embodiments of this invention as it is believed the description will enable those skilled in the art to embody or adapt my invention as may be desired.

Having thus described my invention, what I claim as new and desire to secure by Letters Patent is:

1. In a priming device of the class described the com-

bination of a main float chamber adapted for connection to a pump to be primed and provided with a combined manually operated inlet and drain valve, an auxiliary float chamber disposed above said main float chamber and having an air inlet connection and a water drain and main float chamber air inlet connection to said main float chamber and also having a suction line connection provided with a manually operated valve, a valve for said auxiliary float chamber air inlet connection to said main float chamber, a main float in said main float chamber operatively connected to said auxiliary chamber air inlet valve, an upwardly seating suction actuated check valve for said auxiliary float chamber drain and main float chamber air inlet adapted to be seated by suction in said auxiliary float chamber and also by water in the said main float chamber in the event of the flooding thereof, a float in said auxiliary chamber, a suction line cut-off and air inlet valve disposed in advance of said manually operated suction line valve and operatively connected to said auxiliary chamber float to be closed thereby in the event of water in said auxiliary float chamber reaching a predetermined level, and a manually operated means for simultaneously opening said main float chamber inlet valve and said manually operated suction line valve, said means being spring biased to valve closing position.

2. In a priming device of the class described the combination of a main float chamber adapted for connection to a pump to be primed and provided with a combined manually operated inlet and drain valve, an auxiliary float chamber disposed above said main float chamber and having an air inlet connection and a water drain and main float chamber air inlet connection to said main float chamber and also having a suction line connection provided with a manually operated suction control and air inlet valve, a valve for said auxiliary float chamber air inlet connection to said main float chamber, a main float in said main float chamber operatively connected to said auxiliary chamber air inlet valve, an upwardly seating suction actuated check valve for said auxiliary float chamber drain and main float chamber air inlet adapted to be seated by suction in said auxiliary float chamber and also by water in the said main float chamber in the event of the flooding thereof, a float in said auxiliary chamber, and a suction line cut-off valve disposed in advance of said manually operated suction line valve and operatively connected to said auxiliary chamber float to be closed thereby in the event of water in said auxiliary float chamber reaching a predetermined level.

3. In a priming device of the class described the combination of a main float chamber adapted for connection to a pump to be primed and provided with a combined manually operated inlet and drain valve, an auxiliary float chamber disposed above said main float chamber and having an air inlet connection and a water drain and main float chamber air inlet connection to said main float chamber and also having a suction line connection provided with a manually operated suction control and air inlet valve, a valve for said auxiliary float chamber air inlet connection to said main float chamber, an air vent valve for said auxiliary float chamber operatively connected to said inlet valve thereof to be closed when said air inlet valve is open and to be opened when said air inlet valve is closed, a main float in said main float chamber operatively connected to said auxiliary chamber air inlet valve, an upwardly seating suction actuated check valve for said auxiliary float chamber drain and main float

chamber air inlet adapted to be seated by suction in said auxiliary float chamber and also by water in the said main float chamber in the event of the flooding thereof, a float in said auxiliary chamber, and a suction line cut-off valve disposed in advance of said manually operated suction line valve and operatively connected to said auxiliary chamber float to be closed thereby in the event of water in said auxiliary float chamber reaching a predetermined level.

4. In a priming device of the class described the combination of a main float chamber adapted for connection to a pump to be primed and provided with a combined manually operated inlet and drain valve, an auxiliary float chamber disposed above said main float chamber and having an air inlet connection and a water drain and main float chamber air inlet connection to said main float chamber and also having a suction line connection provided with a manually operated suction control and air inlet valve, a valve for said auxiliary float chamber air inlet connection to said main float chamber, a main float in said main float chamber operatively connected to said auxiliary chamber air inlet valve, a suction actuated check valve for said auxiliary float chamber drain and main float chamber air inlet adapted to be seated by suction in said auxiliary float chamber and also by water in the said main float chamber in the event of the flooding thereof, a float in said auxiliary chamber, and a suction line cut-off valve disposed in advance of said manually operated suction line valve and operatively connected to said auxiliary chamber float to be closed thereby in the event of water in said auxiliary float chamber reaching a predetermined level.

5. In a priming device of the class described the combination of a main float chamber adapted for connection to a pump to be primed and provided with a manually operated inlet valve, an auxiliary float chamber disposed above said main float chamber and having an air inlet connection and a water drain and main float chamber air inlet connection to said main float chamber and also having a suction line connection provided with a manually operated suction control and air venting valve, a valve for said auxiliary float chamber air inlet connection to said main float chamber, an air vent valve for said auxiliary float chamber operatively connected to said inlet valve thereof to be closed when said air inlet valve is open and to be opened when said air inlet valve is closed, a main float in said main float chamber operatively connected to said auxiliary chamber air inlet valve, a suction actuated check valve for said auxiliary float chamber drain and main float chamber air inlet adapted to be seated by suction in said auxiliary float chamber and also by water in the said main float chamber in the event of the flooding thereof, a float in said auxiliary chamber, and a suction line cut-off valve disposed in advance of said manually operated suction line valve and operatively connected to said auxiliary chamber float to be closed thereby in the event of water in said auxiliary float chamber reaching a predetermined level.
